UNITED STATES PATENT OFFICE.

FRANZ PILLER, SR., OF MUNICH, GERMANY.

ARTICLE-DISPENSING PACKAGE.

Application filed May 19, 1925. Serial No. 31,261.

To all whom it may concern:

Be it known that I, FRANZ PILLER, Senior, a citizen of Germany, and residing at Munich, Germany, have invented certain 5 new and useful Improvements in Article-Dispensing Packages, of which the following is a specification.

The present invention relates to improvements in packages for dispensing small articles, such as cigarettes, candy, and the like, and it is directed more particularly to a package for the purpose set forth which, while cheap in manufacture, will operate reliably for the discharge of single objects 15 or a row thereof at a time, without danger of the articles being damaged by the mechanism.

According to my invention the articles to be dispensed are stackedly superimposed 20 within a container upon a spring-influenced false bottom which pushes them forward toward the mouth of the case where they are prevented from being pushed out entirely by overhanging stop elements. The articles 25 are discharged from the case by being pushed out sidewise by finger pressure through lateral openings in the case wall temporarily uncovered by the swinging case lid.

By way of example I have shown and will 30 now describe my improvement in connection with a cigarette case or package, but it is obvious that also other suitable objects may be handled in the same manner.

In the accompanying drawing Fig. 1 is a 35 vertical section through the package on line 1—1 of Fig. 2, which latter figure is a section taken at an angle of 90 degrees to that of Fig. 1. Fig. 3 is a top view of the device, with opened and partly broken-away lid. Fig. 4 is a fragmentary side elevation of a 40 constructional modification.

Referring first to the embodiment according to Figs. 1, 2 and 3, the reference character *a* denotes the article to be dispensed, in this instance cigarettes; *b* is the case, of any suitable material, to which is swingingly hinged the arched lid *f*. As shown, merely 45 by way of example, the cigarettes are arranged in the container in two stacked rows and these two stacks are separated from one another by guide and partition strips of stiff material *c*, one at either end, extending down to the bottom of the case and curved outwardly at the upper extremity in respect

tively opposite direction to form overhanging stop elements or lips *c'*, as clearly shown in Fig. 1. On these separators *c* is loosely guided the false bottom *d*, between which and the true bottom of the case the push 60 spring *e* is positioned. The individual cigarettes in each stack are preferably separated by interposed leaves *g* of paper or similar material. These leaves *g* form horizontal partitions or supplementary false bottoms. 65 They are provided with slots whereby they are loosely engaged with the guide strips *e*, allowing them to be slipped off over the guards *c'* to permit removal of the cigarettes from the package as they come into discharge position following the removal of the first two cigarettes.

The lid *f* is so hinged to the side walls of the case that it can be swung sideways to expose the one or the other half of the case 70 mouth, suitable means being preferably provided, such as stops, to prevent the lid from swinging around too far.

Each narrow side wall of the case is cut 75 away in trough shape at the upper extremity as at *a'*, the bottom of these cut-outs being in alinement with one another and the height thereof being substantially equal to the diameter of the cigarettes or other article 80 handled.

For removing a cigarette from the case the lid *f* is swung around far enough to uncover 85 one-half of the case mouth, which means one-half of the lateral wall cut-outs, the right or the left depending upon which side 90 the lid is swung into (Fig. 1) when a cigarette is shown held between the case wall and the respective overhanging lip *c'*. The cigarette is now pushed out of the case in 95 sidewise direction (as shown in dotted outline in Fig. 2) toward either side by finger pressure, the cigarette passing through the respective cut-out *a'*. The stack of cigarettes then ascends under the pressure of the spring *e* until the next uppermost cigarette contacts with the lip *c'* and is then in turn in the proper position for being pushed out, as described.

I may also dispense with the separator 100 and stop means entirely and control the feeding and dispensing operation solely by the lid.

In the modification shown in Fig. 4 there 105 is used an arched bridge or stop member *c''* extending clear across from side to side 110

of the case mouth, and which preferably consists of a strip of stiff material inserted in the case, or extending integrally therefrom. The lid ⁶ in this instance is preferably one-sidedly hinged to swing back far enough to clear the entire case mouth, so that always all cigarettes in a lateral row can be pushed out at once.

Obviously, the arrangement is not restricted to the use of only two adjacent stacks of dispensable articles, and only one stack or more than two may be used to suit requirements.

What I claim is:—

1. In a dispensing package of the type set forth, in combination with a case open at one end, a lid hinged thereto, means in said case urging the articles to be dispensed toward its open end, and stationary article stop means separate from the lid and arching over the open end of the case below the lid at a distance sufficient to overhang and allow of the articles being pushed out sideways between the edge of the case and said stop means when the lid is opened.

2. In a dispensing package of the type set forth, in combination with a case open at one end and presenting cut-outs in the edges of its two narrow walls, a lid hingedly secured to said case and adapted to be swung around to either side to a sufficient extent to uncover said lateral wall cut-outs, an upwardly urged false bottom in said case adapted to support the articles to be dispensed, and means arching over the mouth of the case designed to retain the uppermost article in alinement with said lateral cut-outs.

3. In a dispensing package of the type set forth, in combination with a case open at one end and presenting outwardly opening article discharge openings in its two opposed narrow walls, separator strips extending from the bottom of the case to somewhat beyond the open end thereof and their free extremities outwardly curved to form overhanging stops, a forwardly urged false bottom in the case, a lid hinged to the case and adapted to be limitedly swung from side to side to uncover only restricted portions of said discharge openings.

4. In a dispensing package of the type set forth, in combination with the case open at one end and presenting alined cut-outs in the free edges of its two narrow walls, a lid hinged to said case for limited swinging displacement to uncover part or all of said cut-outs, a forwardly urged false bottom in said case, separator members fixed in said case and their free extremities outwardly curved to form article stop members, and spacer elements interposed between the individual articles in each stack.

5. In a dispensing package of the type set forth, a case open at one end, at least two

diametrically opposite edge walls of the case at its open end being cut away and lying below the plane of the remaining edge wall or walls, an upwardly urged false bottom in said case adapted to support the articles to be dispensed, and fixed stop means arching over the mouth of the case designed to retain the uppermost article in alinement with the opposed edge walls lying below the level of the others so as to allow a thumb or finger of the operator to be inserted over one cut-away edge wall to push an exposed article from beneath the stop and outwardly over the other cutaway top wall.

6. A dispensing package comprising a case having a discharge opening at one end thereof, pressure means within the case for feeding a stack of articles toward said opening so as to be successively presented for discharge through said opening in a direction laterally of the line of feed, and stop means arranged to overlie an advanced article of the stack disposed in position for discharge, said stop means being operative to prevent discharge of the advanced article in the direction of the line of feed under pressure of said feeding means while admitting external exposure of said article to permit it to be engaged by a thumb or finger of the operator at one side of the package and pushed outward beneath said stop means toward the opposite side of the package for discharge.

7. A dispensing package comprising a case having an open end, a closure for the open end of the case, pressure means for feeding a stack of articles contained within the case toward the said open end thereof, and stop means for arresting feeding motion of the stack and holding an advanced article of the stack from discharge in the direction of the line of feed through the open end of the case when the closure is opened, while holding such advanced article in accessible position to be engaged by a thumb or finger of the operator at one side of the case and pushed outward and discharged in a direction laterally of the line of feed at the opposite side of the case.

8. A dispensing package comprising a case open at one end, means in said case for urging articles contained therein toward said open end of the case, a cover for such end of the case, and stop means positioned at such open end of the case below the cover but above the plane of a wall of the case for arresting the movement of an article and holding such article from displacement when the cover is opened while permitting the article to be pushed out on a line between such edge of the case and said stop means.

9. A dispensing package comprising a case open at one end, means in said case for urging articles contained therein toward said open end of the case, such end of the case

having an edge wall cutaway below the plane of other edge walls thereof, and a stationary stop device at such open end of the case arranged to overhang and arrest the movement of an article and prevent its displacement from the case in the direction of the line of feed under the action of said urging means, said stop device forming with such cutaway edge wall of the case guides above and below the stopped article permitting the article to be pushed out at the open end of the case on a line between said stop means and said wall.

10. A dispensing package comprising a case open at one end, a cover for normally closing the open end of the case, pressure

means within the case for feeding a stack of articles toward the open end thereof, and a stationary stop independent of the cover and arranged at the open end of the case so as to be engaged by an advanced article of the stack, said stop being operatively disposed to hold the stack from outward movement in the direction of its line of feed when the cover is opened while exposing an advanced article engaged thereby so as to permit said article to be engaged by the finger or thumb of the operator at one side of the case and forced laterally from beneath the stop and discharged at the opposite side of the case.

FRANZ PILLER, SEN.
